UNITED STATES PATENT OFFICE

HENRY J. McCARTHY, OF WATERBURY, CONNECTICUT, ASSIGNOR TO SCOVILL MANUFACTURING COMPANY, OF WATERBURY, CONNECTICUT, A CORPORATION OF CONNECTICUT

MEANS FOR ATTACHING HANDLES TO TRAYS AND THE LIKE

Application filed March 24, 1928. Serial No. 264,508.

This invention relates to certain improvements in articles having a surface finish, such as trays or the like, with which handles are associated, and to an improved method for associating the handles with such articles.

5 Various articles, such as trays or the like, have applied thereto and to their handles a surface finish, which finish may be of various kinds, as, for instance, a polished or enameled finish, or the like. If the handle were first attached to the tray, such finishing would be difficult and expensive, and if the handle and article were finished separately, it would be necessary to subsequently assemble them 10 without injuring the finish of either.

15 It is the especial object of the present invention to provide an improved method and means for assembling a handle with the article in such a manner that a surface finish applied to either the handle or the article, or both, is in no way damaged or injured when permanently associating the article and its handle so that the two parts may be separately finished and then permanently associated.

20 A further object of the invention is to provide a simple means whereby this can be accomplished of such character that the association of the parts may be readily and quickly effected, and by the use of which the 25 parts are permanently and securely held together.

30 With these and other objects not specifically referred to in view, the invention consists in certain novel parts, arrangements and 35 combinations which will be described in the accompanying drawings and the novel features pointed out in the claims hereunto annexed.

35 In these drawings,—
40 Figure 1 is a perspective view of a shallow tray having a handle secured thereto at opposite sides;

45 Figure 2 is a partially broken away side view looking in the direction of arrow 2 of Figure 1, on an enlarged scale, and

50 Figure 3 is a sectional view taken on line 3—3 of Figure 2.

55 Referring now to these drawings in detail, the article chosen to illustrate the invention is in the form of a shallow tray,

such as an ash tray, having a handle associated therewith on opposite sides. It will be understood, however, that such an article has been selected as merely illustrative of the invention and the invention as to its important features may be used in associating a handle with a finished article of various forms.

60 Referring to the construction shown, however, there is provided a tray 1 which is provided with a handle 2. In the particular embodiment of the invention illustrated, the tray 1 and the handle 2 are both highly finished, as by polishing or enameling. In accordance with the invention, means are provided whereby these parts may be associated together after they have been finished without the use of welding or solder, so that the surface finish is in no way injured during assembly.

65 While the particular means for effecting this may be somewhat varied, in the particular arrangement illustrated the tray before it is finished has secured thereto a pair of sockets which are shown in the form of narrow strips 3, 4 of deformable metal. These strips may be soldered or welded to the under surface of the tray and, as this is done before the tray is finished, any irregularities caused by such treatment are eliminated in the finishing process, so that the tray and its strips 70 may be treated as desired after the strips have been secured in place.

75 These strips are, as shown at 5 in Figure 2, formed with offsets which space the center part of the strips away from the surface of 80 the tray. The handle is formed with extensions 6 which are connected by a cross-piece 7. The extensions and the cross-piece are dimensioned to slip through the openings left between the strips and the tray, the cross-piece extending beyond or inside the strips, as clearly shown in Figure 3. The center part of the strip is then deformed, as by pinching or bending it inwardly as indicated at 8 in Figure 2, this being preferably bent in sufficiently to extend above the plane of the cross-piece 7, as clearly shown in Figure 3, so that this acts as a stop and prevents the withdrawal of the extension members of the handle.

100

With this construction it will be seen that the handle and tray may be readily and quickly associated after they have been finished without there being any danger of marring or otherwise injuring the finish of either of the parts. The strips being secured to the tray prior to finishing partake of whatever finish is applied to the tray surface. A very neat and attractive article is thus produced and one which can be readily and quickly assembled.

While the invention has been shown and described in its preferred form, it will be understood that certain changes and variations may be made in the particular construction adopted and that the invention is applicable to associating handles with articles of widely varying forms.

What I claim is:

20 1. A receptacle having a finished surface, strips of deformable metal secured beneath the surface of the receptacle before it is finished and spaced therefrom, and a handle having inwardly turned extensions fitting under the strips and held in place by pinching the strips down on the extensions.

25 2. A receptacle having a finished surface, strips of deformable metal secured to the receptacle before it is finished and spaced from the surface of the receptacle, and a handle having inwardly turned extensions fitting under the strips, and members located behind the strips, the metal of the strips being bent downwardly below the plane of the members 35 behind the strips so that the handle is firmly locked in place.

In testimony whereof, I have hereunto set my hand.

HENRY J. McCARTHY.
